J. S. HOUGHTON AND CHARLES B. REES, OF PHILADELPHIA, PENNSYLVANIA.

Letters Patent No. 83,163, dated October 20, 1868.

IMPROVEMENT IN VENTILATING FRUIT-HOUSES.

The Schedule referred to in these Letters Patent and making part of the same.

To all whom it may concern:

Be it known that we, J. S. HOUGHTON and CHARLES B. REES, of the city and county of Philadelphia, and State of Pennsylvania, have invented a new and improved Mode of Ventilating Fruit and Meat-Preserving Houses; and we do hereby declare that the following is a full and exact description thereof, reference being had to the accompanying drawings, and to the letters of reference marked thereon.

The nature of our invention consists in the ventilation of rooms, cooled by ice, through a hollow wall, at a point remote from the ice-chamber, into a ventilated loft.

The accompanying drawing represents a vertical section of the improved house.

A represent the walls of the building, there being open spaces, B, from the top of the preserving-room C, through the wall, communicating with the ventilated loft D, for carrying off the heat, vapors, and gases, from the preserving-room C. There are packed spaces, E, outside the wall A, to prevent the heat penetrating through the wall; and there are packed spaces, F, around the ice-chamber G, to prevent the cooling of the vapors as they ascend through the ventilating hollow wall.

What we claim as our invention, and desire to secure by Letters Patent, is—

The combination and arrangement of the open spaces or flues, B, in the walls A, with the preserving-room C, and ventilated loft D, substantially as described.

In testimony that the above is our invention, we have hereunto set our hands, and affixed our seals, this 30th day of April, 1868.
